UNITED STATES PATENT OFFICE.

JOHANN STRAUBINGER, OF NEWARK, NEW JERSEY.

PADLOCK.

SPECIFICATION forming part of Letters Patent No. 417,602, dated December 17, 1889.

Application filed October 2, 1888. Serial No. 286,982. (Model.)

To all whom it may concern:

Be it known that I, JOHANN STRAUBINGER, a citizen of the United States, residing at Newark, in the county of Essex and State of New Jersey, have invented certain new and useful Improvements in Locks; and I do hereby declare the following to be a full, clear, and exact description of the invention, such as will enable others skilled in the art to which it appertains to make and use the same, reference being had to the accompanying drawings, and to letters of reference marked thereon, which form a part of this specification.

15 The object of this invention is to simplify the construction of spring-padlocks, to reduce the number of parts required in their construction, and at the same time make a stronger and more efficient lock than has 20 heretofore been made.

The invention consists in the improved lock and in the combinations and arrangements of parts thereof, substantially as will be hereinafter set forth, and finally embodied in the claim.

25 Referring to the accompanying drawings, in which like letters of reference indicate similar parts in each of the several figures, Figure 1 is a plan view of a lock with the top 30 plate removed embodying my improvement, showing the parts locked. Fig. 2 is a plan view of the same, showing the key in position, with the parts unlocked. Fig. 3 is a section through line X, Fig. 1; and Fig. 4 is a section through line Y, Fig. 2.

35 In said drawings, *a* indicates a lock-case. *b* is a sliding bolt formed at its outward end with a hoop divided into two parts *b'* and *b''* and pivoted together at *b³*. The outside end 40 of the part *b'* is provided with a projection *b⁴* and rounded, as at *b⁵*, Fig. 2. This projection is so constructed that when the parts *b'* and *b''* are swung together it shall lie parallel with the bolt *b*, as shown in Fig. 1.

45 *b⁶* is a stop made integral with the bolt *b*, and limits the outward motion of the bolt *b* in the case *a* by coming in contact with the stop *a'*, cast upon and made integral with the under plate of the case *a*.

50 *a²* and *a³* are guides made integral with the plate of case *a*, and between which the bolt *b*

slides. The guide *a²* is slotted, so as to allow the free passage of tumblers *c* *c'* between the upper and lower plates of the case *a*. The upper side of the rod *b* is also slotted transversely to allow the passage of the tumblers *c* *c'* and engagement therewith. These tumblers are slotted on their upper sides, so as to allow the admission of a key *d*. One of the walls of the slot is made straight and at right angles, as shown at *c²*, and the other wall is convex, as shown at *c³*, so as to be acted upon by the key, as will be hereinafter described.

Upon the under side of the tumblers *c* and *c'* are grooves or slots *c⁴* *c⁴'*, in which the bolt *b* can slide when the tumblers are brought into the position shown in Fig. 2.

e is a wire spring, one end resting against the inner periphery of the case *a*, and the other end resting in a slot *e'* on the under side of the tumbler *c'*, and is held in position by a pin *e²*, projecting upward from the lower plate of the case *a*. *f* is a similar spring, and connected in the same manner with the tumbler *c*.

55 *g*, Fig. 1, is a projection extending upward from the lower plate of case *a*, between which and the guide *a³* the key *d* slides.

g' is a slot in the outer periphery of the case to allow the admission of the key *d*.

60 *h* is another opening in the periphery of the case to allow the passage of the bolt *b* and the extending projection *b⁴*.

h' is an inwardly-extending projection at one side of the slot *h*, forming an additional support for the part *b⁴*.

65 The key *d* is constructed with one side straight and the other of irregular curves and angles, as shown in Fig. 2, so as to press upon the tumblers, as will be readily understood.

70 *m* is a pin or stud extending downward from the upper plate and resting upon the upper part of the bolt *b* to keep it in position. This pin is shown in dotted lines in Figs. 1 and 2 and in section in Fig. 4.

75 When it is desired to unlock the device, the key *d* is inserted in the slot *g'*, with the straight side toward the center. When the point of the key reaches the convex side or portion *c³* of the tumbler *c'*, it will force the tumbler to the right and allow the key to pass farther until the point reaches the con-

vex portion c^3 of the tumbler c , which tumbler, in its turn, as the key is pressed in, is forced to the right in like manner until the tumblers and the key are in the position 5 shown in Fig. 2. The slot on the under side of the tumblers will then be both in a straight and continuous line, and the bolt b , with the part b^4 , can then be drawn out until the part b^4 is entirely free from contact with the case 10 a . In this position the part b' can be turned on the pivot b^3 , as shown in Fig. 2, thus releasing whatever had been locked or secured, as will be manifest.

Having thus described the invention, what 15 I claim as new, and desire to secure by Letters Patent, is—

A lock constructed substantially as herein shown and described, consisting of a case, a sliding bolt b , formed at its outer end with a 20 hoop divided into two parts and pivoted together, one of said parts being provided with

an extension to enter a slot in the case and in juxtaposition with the bolt b , said bolt being also provided with transverse slots on its upper surface to allow the passage of sliding tumblers $c c'$, provided with slots on their upper sides, with convex walls on one side, against which the key acts, and with slots on their under sides to allow the passage of the bolt b , springs e and f , adapted to hold said 25 tumblers in position, and guides for the tumblers and the key, and integral with one of the case-plates, all said parts being arranged for operation as and for the purposes set forth.

In testimony that I claim the foregoing I have hereunto set my hand this 24th day of September, 1888.

JOHANN STRAUBINGER.
